UNITED STATES PATENT OFFICE.

SAMUEL A. STRZELCZYK, OF MILWAUKEE, WISCONSIN.

HOUSEHOLD GRINDING WHEEL.

Application filed February 10, 1921. Serial No. 443,905.

To all whom it may concern:

Be it known that I, SAMUEL A. STRZELCZYK, a citizen of the United States, and resident of Milwaukee, in the county of Milwaukee and State of Wisconsin, have invented certain new and useful Improvements in Household Grinding Wheels; and I do hereby declare that the following is a full, clear, and exact description thereof.

10 My invention relates to new and useful improvements in grinding wheel structures, and is more particularly directed to the provision of a grinding wheel structure of exceedingly simple nature and adapted more particularly for household uses.

15 In the ordinary household, considerable use is found for a grinding wheel under conditions which impart comparatively little strain or wear as in sharpening kitchen knives and the like. It is therefore primarily the object of my invention to provide a grinding wheel which is of sufficient strength and durability to meet ordinary household conditions and which may be 20 manufactured with a minimum expenditure of time, labor and material, it being more specifically an object to provide a grinding wheel and clamp attaching member therefor constructed almost entirely of wood.

25 A further object resides in the provision of a clamping member for mounting the wheel, including portions cut from a single block of wood in such manner as to procure a maximum coacting clamping expanse of 30 said members.

35 With the above and other objects and advantages in view the invention resides more particularly in the novel combination, formation and arrangement of parts more particularly hereinafter described and pointed out in the appended claims.

In the drawings:

Figure 1 is a side elevational view of a grinding wheel structure constructed in accordance with my invention, and with portions thereof broken away.

Figure 2 is an end view of the structure.

In forming my improved grinding wheel structure, there is provided a body block 5 and one end of this body block is turned to provide an integrally projecting journal pindle 6 for the grinding wheel. The other end of the block forms a clamping member and a coacting clamping bar 7 is formed by 50 slitting the body longitudinally from said other end, and then cutting the block trans-

versely at an acute angle whereby to provide for detachment of the bar portion 7. A clamping bolt 8 having a wing nut 9 thereon is passed through the bar 7 and through the body block and the inner end of the bar seats on the top face of the block. Thus by transversely cutting the block at an acute angle to the longitudinal slit, the top face of the block and the bottom face of the bar 7 are afforded relatively greater lengths than if the cut were made at right angles, and the outer ends of the block and clamping bar 7 may be disposed in the same plane, with their inner ends in lapped abutting relation, whereby to procure a maximum clamping action. The inner end of the bar 7 is loosely coupled to the top of the block by a pair of interlocked staples 10 driven in said end and top of the block, the 70 only function of these staples being to prevent rotative movement of the bar on the bolt 8.

The grinding wheel comprises a circular wooden disc 11 journalled on the pindle 6, 80 and secured against displacement therefrom by a nail 12 driven through a retaining cap 13 into the end of the pindle. Projecting outwardly from the disc adjacent its periphery is a screw bolt 14 on which is mounted a handle sleeve 15 retained against displacement by the head of the bolt. Glued on the periphery of the disk is a strip of emery paper or other suitable abrasive material 16, and to secure the ends of said 90 strip, said ends are tucked into a radial slit 17 in the peripheral portion of the disk.

By the foregoing description a grinding wheel structure has been provided which may be manufactured at an exceedingly low 95 cost, the only metallic part involved, apart from the nails and screws being the small cap plate 13. In forming the mounting for the wheel, the body block 5 is first cut from a length of wood, and placed in a lathe to 100 form the integral pindle 6. A bore for the clamping bolt is then made and the block is cut to form the bar portion 7 which is secured to the body block by the bolt 8 and staples 10. The wheel and its disk is 105 formed in correspondingly simple and few steps, and the economy of labor procured in addition to the economy of material permits an obviously very small cost of manufacture.

110 It is noted that the enlarged pindle end portion of the body block formed by cutting

out the bar portion 7 affords a bearing support for the wheel and disk to prevent wobbly movement thereof, in addition to providing a spacing means for the block and 5 bar to receive the edge of a table or other support.

For honing knives or the like, the top face of the clamping bar 7 has secured thereto a strip of suitable honing material 18.

10 What is claimed:

1. A device of the class described comprising a body block, a pintle at one end of the body block, a disk mounted on said pintle, said body block being slit longitudinally 15 from its other end and being cut transversely to form a separate clamping bar portion, a clamping bolt passed through said clamping bar portion and the block, and means loosely connecting the adjacent end 20 of the clamping bar and the pintle end portion of the block whereby said end of the

bar is retained in lapped relation with the said portion of the block.

2. A device of the class described comprising a body block, a pintle at one end 25 of the body block, a disk mounted on said pintle, said body block being slit longitudinally from its other end and being cut transversely to form a separate clamping bar portion, a clamping bolt passed through 30 said clamping bar portion and the block and interlocked staples driven into the clamping bar and the pintle end portion of the block, whereby the adjacent end of the bar is loosely retained in lapped relation with 35 the adjacent portion of the block.

In testimony that I claim the foregoing I have hereunto set my hand at Milwaukee, in the county of Milwaukee and State of Wisconsin.

SAMUEL A. STRZELCZYK.
